[57] CLAIM

The ornamental design for an ash urn, as shown and described.

DESCRIPTION

FIG. 1 is a perspective view of an ash urn which embodies my design;

FIG. 2 is a front elevational view thereof, the rear elevational view thereof being a mirror image thereof;

FIG. 3 is a right side elevational view thereof, the left side elevational view being a mirror image thereof;

FIG. 4 is a bottom plan view thereof;

FIG. 5 is a top plan view thereof;

FIG. 6 is a perspective view of a second embodiment of an ash urn which embodies my design;

FIG. 7 is a left side elevational view thereof;

FIG. 8 is a front elevational view thereof, the rear elevational view being a mirror image thereof;

FIG. 9 is a right side elevational view thereof;

FIG. 10 is a top plan view thereof; and,

FIG. 11 is a bottom plan view thereof.
